(57) **CLAIM**

The ornamental design for a label, as shown and described.

DESCRIPTION

FIG. 1 is a front view of a label showing my new design; FIG. 2 is a rear view thereof;

FIG. 3 is a reference view of usage thereof, with the upper layer removed for clarity of disclosure; and, FIG. 4 is a front view showing upper layer is removed thereof.

The elements shown in phantom lines do not form any part of the claimed design.

1 Claim, 2 Drawing Sheets*FIG. 1*

FIG. 2

FIG. 3**FIG. 4**
